UNITED STATES PATENT OFFICE.

JAMES G. McNAMARA, OF BROOKLYN, NEW YORK, ASSIGNOR TO MERGENTHALER LINOTYPE COMPANY, A CORPORATION OF NEW YORK.

TYPOGRAPHICAL COMPOSING MACHINE.

Application filed April 30, 1924. Serial No. 709,970.

This invention has reference to typographical composing machines, such as linotype machines of the general organization represented in Letters Patent of the United States to O. Mergenthaler, No. 436,532, wherein circulating matrices are released from a channeled magazine by key-controlled escapement mechanism in the order in which the characters are to appear in print, and then assembled in line, the composed line transferred to the face of a mold, the mold filled with molten metal to form a slug or linotype against the matrices, which produce the type characters thereon, and the matrices thereafter returned through a distributing mechanism to the magazine from which they started.

The present invention is directed primarily to an improved form and construction of the escapement mechanism and aims to prevent injury to the parts in the event of obstruction being offered to the normal operation of said mechanism, as by the clogging or misplacement of the matrices, or from other causes, all as will be fully pointed out in the detailed description to follow.

In the accompanying drawings, the invention is shown as applied to a machine equipped with a series of shiftable magazines, but it will be obvious that it might be applied to a single magazine machine, if desired, or to a machine of any other kind.

Referring to the drawings:

Fig. 1 is a vertical section through the magazine structure and keyboard mechanism of a linotype machine equipped with this invention;

Fig. 2 is a plan view of the improved escapement mechanism;

Fig. 3 is a perspective view of one of the escapements detached;

Fig. 4 is a view similar to Fig. 1 but showing the invention in modified form.

As shown in Figs. 1 and 4, the magazine structure comprises two channeled magazines 1, arranged one over the other and supported upon underlying base frames 2, the whole structure being shiftable as a unit in the well known manner to bring one or the other of the magazines into operative relation to a stationary assembler entrance 3, into which the matrices 4 are delivered when released from the operative magazine, and by which they are directed to the assembling point for composition in line. Each of the

individual magazines consists, as usual, of parallel top and bottom plates suitably spaced apart and provided in their opposing faces with longitudinal grooves 5 to receive and guide the matrices by their upper and lower ears 6 as they pass through the magazine by gravity. To effect the release of the matrices one at a time from either selected magazine, each channel thereof is provided with an escapement mechanism of improved form and construction.

In accordance with this invention (reference being made to Figs. 1 to 3), each escapement mechanism comprises a verge or escapement lever 7 pivoted between its ends, as at 8, to a supporting bar or frame 9 suitably sustained by the base frame of the magazine. (The manner in which the escapement bar is supported constitutes no part of the present invention, the particular embodiment shown forming the subject matter of a separate application.) The escapement lever 7 is provided at its forward end with a pawl 10 and at its rear end with a pawl 11, which pawls extend upwardly through openings in the upper grooved plate of the escapement bar, so that by rocking the escapement lever, the pawls may be projected alternately into the path of the matrices as they pass through the magazine.

A spring 12 has its rear end seated fixedly in the escapement bar and bears at its forward end against the underside of the rear end of the escapement lever, and acts to thrust the rear pawl into the matrix path and retract the front pawl. An actuating lever 13, pivoted to the escapement bar as at 14, has a rearwardly projecting arm 15 extending beneath the front end of the escapement lever, and an upwardly extending arm 16 disposed just inward of the plane of the forward end of the magazine structure. The arm 15 is engaged on its underside by a spring 17 which extends rearwardly beneath the escapement lever and has its rear end seated fixedly in the escapement bar, the tendency of this spring being to rock the actuating lever on its axis so as to engage its arm 15 with the forward end of the escapement lever.

The strength of the spring 17 is greater than that of the spring 12, so that when the actuating lever 13 is free to be rocked by the spring 17, it engages and lifts the forward end of the escapement lever and thereby projects the front pawl 110

into the matrix path and retracts the rear pawl. When however the actuating lever is rocked away from the escapement lever, the spring 12 is permitted to rock the escapement lever in a contrary direction so as to project the rear pawl into the matrix path and retract the front pawl.

The actuating levers 13 of the several escapement mechanisms are controlled in their action by a series of substantially L-shaped operating levers 19, which are pivotally mounted at their lower ends on a horizontal axis 20 with their upper ends arranged in position to engage the arms 16 of the actuating levers of the selected magazine. These operating levers 19 are normally disengaged from the lever arms 16 but are adapted, by the operation of the keyboard mechanism, to be rocked upwardly and rearwardly to engage said arms and rock the lever arms 15 downwardly away from the escapement levers so as thus to allow the springs 12 to function.

The operating levers 19 are rocked upwardly in the foregoing manner by means of the usual vertically reciprocating reeds 21, whose upper ends as shown, are in position to engage the operating levers well in advance of their pivots, and whose lower ends are arranged in position to be engaged by the keyboard cam yokes 22 carrying the usual cams 23. When the cam yokes are tripped by the triggers 24 on the depression of the finger keys, the cams drop into engagement with the rubber rolls 25 and are rotated thereby, which action rocks the cam yokes upwardly and causes a corresponding movement of the operating levers 19, all as well understood in the art.

The operation of the parts above described is as follows:

On the depression of a finger key, its corresponding cam yoke 22 is tripped and by the rotation of the cam 23 the associated reed 21 is elevated to rock the corresponding operating lever 19 upwardly and rearwardly, whereby the engaged actuating lever 13 is rocked to the position shown in Fig. 1. In this action, the front spring 17 is depressed and the arm 15 of the actuating lever 13 disengaged from the escapement lever 7, so that the rear spring 12 is allowed to reverse the position of the escapement lever, thereby retracting the front pawl 10 to release the foremost matrix and at the same time projecting the rear pawl 11 into the path of the next matrix to arrest it momentarily. This action is followed almost instantly by the return of the parts to their former condition, disengagement of the operating lever 19 from the actuating lever 13 permitting the latter, under the influence of the spring 17, to re-engage the escapement lever and rock it back to its original position, thereby withdrawing the

rear pawl 11 from the matrix path and projecting the front pawl 10 to hold the detained matrix until the finger key is again actuated, as shown in connection with the lower magazine.

70

It is to be noted that the movements of the escapement levers are effected only under the influence of the two springs, so that in the event of any obstruction to the movement of the parts, as by the clogging of the matrices, or their misplacement, or from other causes, no damage can result. The arrangement is also useful in taking up the overthrow motion of the keyboard devices and in relieving excessive wear upon the rubber rolls. These and other advantages will be readily appreciated by those skilled in the art.

In Figs. 4, the construction of the escapement mechanism is substantially the same as that above described, but in this case the actuating levers 13^a for the escapement levers are directly controlled in their operation by the keyboard reeds 21^a, which for this purpose are extended upwardly at an inclination, as at 26, so that their upper ends will be in position to engage the actuating levers. The two arms 15^a and 16^a of each lever 13^a are disposed in line with each other, the forward arm 16^a being arranged in position to be engaged and rocked upwardly by the keyboard reed to the position shown on the upper active magazine, and thereby move the rear arm 15^a downwardly out of engagement with the escapement lever in order to allow the spring 12 to actuate the escapement lever. Since the reeds 21^a engage the undersides of the actuating levers 13^a and operate the same by an upward vertical movement, the upper ends of the reeds are disposed inwardly of the plane of the forward ends of the magazines, and hence it is necessary, before the magazines can be shifted, to move the upper ends of the reeds out of the path of the magazines. This is accomplished, in the present instance, by providing a comb plate 26^a through which the reeds extend at their upper ends, which plate is carried by arms 27 pivoted on a horizontal axis 28, so that by rocking the arms the comb plate will shift the upper ends of the reeds into or out of operative relation to the actuating levers. The comb plate may be operated by any suitable means, such for example as a handle 28^a fixed to one of the arms 27 and extending within convenient reach of the operator.

The foregoing improvements have been shown only in preferred form and by way of example, and obviously many changes and modifications may be made therein without departing from the spirit of the invention. It should be understood, therefore, that the invention is not limited to any

125

130

specific form or embodiment except in so far as such limitations are set forth in the appended claims.

Having thus described my invention, what I claim is:

1. In a typographical composing machine, the combination of an escapement lever provided with matrix engaging pawls, a spring acting on the escapement lever to rock it in one direction, a pivoted actuating lever disconnected from but adapted to directly engage the escapement lever and rock it in the opposite direction, a spring for operating said actuating lever and of a strength greater than that of the other spring, and means for controlling the operation of the actuating lever.

2. In a typographical composing machine, the combination of an escapement lever provided with matrix engaging pawls, a spring engaging one end of the escapement lever and acting to rock the same in one direction, a pivoted actuating lever in position to directly engage the other end of the escapement lever and rock it in the opposite direction, a spring acting directly on the actuating lever and of a strength relatively greater than that of the other spring, and means for controlling the operation of the actuating lever.

3. In a typographical composing machine, the combination of a rocking escapement lever provided with matrix engaging pawls, a spring acting on the escapement lever and operating to rock the same in one direction, a pivoted actuating lever provided with two arms, one of which is adapted to engage the escapement lever, a spring acting directly on said lever arm and operating to rock the escapement lever in the opposite direction, and an operating device adapted to engage the other arm of the actuating lever, and move it positively against the action of its spring to allow the escapement lever spring to act.

4. In a typographical composing machine, the combination of an escapement bar, an escapement lever pivoted to said bar and provided with matrix engaging pawls, a spring sustained by the escapement bar and acting on the rear end of the escapement lever to rock the same in one direction, an actuating lever mounted wholly on the escapement bar in position to engage the front end of the escapement lever, a second spring also supported by the escapement bar and bearing on the actuating lever, and an operating device adapted to engage the actuating lever.

5. In a typographical composing machine, the combination of an escapement bar, an escapement lever pivoted to said bar and provided with matrix engaging pawls, a spring bearing at its forward end against the rear end of the escapement lever and having its rear end seated in the escapement bar, an actuating lever pivoted to and carried by the escapement bar in position to engage the front end of the escapement lever, a second spring arranged beneath the escapement lever and engaged at its forward end with the actuating lever and having its rear end seated in the escapement bar, and an operating device adapted to engage the actuating lever.

6. In a typographical composing machine, the combination of an assembler entrance, a plurality of magazines adapted to be shifted to bring any selected one thereof into operative relation to said assembler entrance, a set of escapement mechanisms for each magazine and shiftable with the magazine, each escapement mechanism comprising an escapement lever provided with matrix engaging pawls, a spring acting on the escapement lever to rock it in one direction, an actuating lever adapted to directly engage the escapement lever and rock it in the opposite direction, and a spring for operating said actuating lever and of a strength greater than that of the other spring, and means for controlling the operation of the actuating levers of the operative magazine.

7. In a typographical composing machine, the combination of a plurality of magazines and supporting base frames, adapted to be shifted to bring any selected one thereof into operative position, a set of escapement mechanisms for each magazine comprising an escapement lever pivotally sustained by the base frame and provided with matrix engaging pawls, a spring sustained by the base frame and acting on the escapement lever to rock the same in one direction, an actuating lever pivotally sustained by the base frame and adapted to directly engage the escapement lever and rock the same in the opposite direction, and a second spring sustained by the base frame and engaging the actuating lever, said spring being of a strength greater than that of the other spring, and means for controlling the operation of the actuating levers of the operative magazine.

In testimony whereof, I have affixed my signature hereto.

JAMES G. McNAMARA.
